CLAIM

The ornamental design for a combined infant carrier and bed, as shown and described.

DESCRIPTION

FIG. 1 is a perspective view of a combined infant carrier and bed showing my new design; that portion of the design which is obscured by the canopy being a mirror image of the visible portion;

FIG. 2 is a right side elevational view thereof;

FIG. 3 is a left-side elevational view thereof;

FIG. 4 is a front elevational view thereof;

FIG. 5 is a rear elevational view thereof;

FIG. 6 is a top plan view thereof; and,

FIG. 7 is a bottom plan view thereof.
